United States Patent Office

Des. 176,285
Patented Dec. 6, 1955

176,285

MOBILE HOME

Myron E. Raker, Fort Wayne, Ind.

Application October 14, 1954, Serial No. 32,659

Term of patent 3½ years

(Cl. D14—3)

FIG.1

FIG.3

Fig. 1 is a perspective view of a mobile home embodying my new design;

Fig. 2 is a side elevational view of only the dominant portion of said mobile home; and

Fig. 3 is a front elevational view of said mobile home.

I claim:

The ornamental design for a mobile home, substantially as shown and described.
